UNITED STATES PATENT OFFICE.

JAMES GILLAM WOOD, OF SAN ANTONIO, TEXAS.

BOX-CAR-DOOR FASTENER.

1,364,970.

Specification of Letters Patent. Patented Jan. 11, 1921.

Application filed December 30, 1919. Serial No. 348,268.

To all whom it may concern:

Be it known that I, JAMES G. WOOD, a citizen of the United States, residing at San Antonio, in the county of Bexar and State 5 of Texas, have invented certain new and useful Improvements in Box-Car-Door Fasteners, of which the following is a full, clear, and exact description.

The invention is designed particularly for 10 use in connection with railway box car doors, of the standard sliding type, and embodies a fastening device applicable for use with the well known style of sliding door without necessity for changing or altering the structure 15 of the door or the car in any material way. By the utilization of my invention I am enabled to securely lock or fasten the door in its frame in closed position, or the door may with equal facility be fastened 20 securely with relation to the car in slightly open position or ajar for purpose of ventilating the interior of the car and yet retain the door securely fastened.

To this end the invention consists in certain 25 novel combinations and arrangements of a fastener of the multiple sliding bolt type with a series of selective, movable hasps, and a fixed hasp or keeper for the bolts, together with certain novel features of construction, as will be hereinafter more fully disclosed in the specification and claims.

The accompanying drawings illustrate one 30 complete example of the physical embodiment of my invention in which the parts are combined and arranged according to the best mode I have so far devised for the practical application of the principles of the invention, and it will be understood that colorable 35 changes and alterations may be made in the exemplified structure, within the scope of 40 my claims without departing from the spirit of the invention.

Figure 1 is a side view of a portion of a well known type of railway car equipped 45 with the door fastener of my invention, the door being illustrated in closed and fastened position.

Fig. 2 is a view similar to Fig. 1, but here 50 the door is slightly ajar for the purpose of ventilating the interior of the car, the parts however, being securely fastened, and may be sealed in this position.

Fig. 3 is an enlarged view showing in elevation a portion of the outside of the door 55 with the slide bolts projected and unlatched.

Fig. 4 is a horizontal sectional view of

the door and accessories, on line 4-4 of Fig. 3.

Fig. 5 is an enlarged, detail sectional view 60 of a car side or wall illustrating the selective hasps that are used in conjunction with one of the sliding bolts, the other bolt it being understood has a fixed hasp or keeper, the section being taken at line 5-5 of Fig. 1.

Fig. 6 is a detail section at line 6-6 of Fig. 2 showing the securing latch of the fastening bolts sealed with a lock in dotted lines.

In carrying out my invention and applying 70 the door fastener in actual use, I utilize the type of box-car indicated by the numeral 1 in the drawings, and the sliding door 2, both of well known construction; the latter guided by the shoes 3, 3, near the lower 75 edge of the side of the car, and suspended at its upper end, or top, in usual manner for such sliding doors.

The members of the fastening device are 80 jointly carried by the door and the car; on the door there being arranged in alinement, a pair of oppositely sliding, complementary bolts 4 and 5, located, to be moved horizontally, at a convenient and accessible height on the door, to be manipulated with facility 85 when required, and each bolt is fashioned with a bent or angular end 6 to be utilized as a lever handle when fastening or unfastening the door closure. These bolts are 90 cylindrical in cross section, as for instance they may be made up of round steel bars with bent inner ends, and are slidable in 95 their supporting bearings 7, 7, and also, rotatable therein.

The inner ends of the bolts are located adjacent 95 the vertical center line of the door, and at the proper point in alinement with the bolts, which are approximately half the width of the door, a stop or abutment block 8 is secured to the door to prevent excessive 100 or undue inward movement of the bolts, the bent lever handles being adapted to contact with or abut against the stop, as will readily be understood.

One of the bolts, as 4, is adapted to engage 105 and co-act with a fixed keeper 9, which may be in the form of a perforated metallic plate, secured inside the car at the edge of the door frame in position to receive the free end of the bolt, and both bolts, it will be noted, 110 at their outer or free ends, are fashioned with slightly rounded and flattened or cut-

away portions 10 at the side of the bolt from which the lever handle projects. The bolts are thus specifically designed to form cam friction faces, of which the flattened portion will engage the near wall of the bolt aperture in the keeper when the bolt is inserted therein with the lever handle in outwardly projecting, horizontal position, the bolt being inserted in the keeper with the required freedom of movement. Now when the bolt is rotated and, its handle turned down to vertical position in Fig. 1, the full round face of the bolt opposite the flattened face will frictionally engage the same near wall of the aperture in the keeper, thus forcing the door inwardly in alinement with the side of the car. Of course, when the door is suspended and sliding to closed, or partially closed position, the necessary, limited freedom of lateral movement of the door is permitted in the cleats 3, but when the closed position has been reached and the lever handle is turned down, the door is tightly jammed into the door frame 11 and thus securely held against rattling or working loose.

The oppositely working bolt 5 is adapted to co-act with a selected keeper 12, 13, 14, in a group, or the spaced outermost single hasp 15 completing the series of keepers, located at the rear end of the door and supported in the side of the car. The series of drop blocks or movable keepers for the bolt 5 are pivoted on a fixed bar or rod 16 supported inside the car wall and incased in a housing 17, slots 18 being fashioned in the car side or wall to accommodate the blocks, which are in the form of plates with a pair of perforations, one to journal the block on its bearing rod 16 and the other to receive the bolt end. The blocks are pivoted on the rod, and because of their shape, the weighted ends cause them to fall by gravity to vertical position within the housing and slot when not in use, but may with facility be pulled out to horizontal position when a selected one is to be used as a keeper for the bolt 5. In Fig. 1 the block 12 is in use and the door is fastened in entirely closed position, while in Fig. 2 the door is only partially closed, the bolt 4 being locked in its keeper 9 and the bolt 5 being secured in the block 15. In Fig. 2 the door is ajar, but fastened, to allow for ventilating the interior of the car, when necessary, for the benefit of the contents or cargo.

A specially constructed sliding latch 19 is provided for the two bolts, and is of sufficient length to contact with and retain both of the lever handles of the bolts in any of their adjusted positions, the latch being located below the bolts and in parallel relation thereto and supported on the door by the base plate 20 of metal and fashioned with the retaining guide loop or band 21

and guide lugs 21' shown as integral with the plate and turned to opposed positions for guiding the latch bar, and retaining it in contact with the downturned lever handles of the bolts.

The base plate may be cast, or wrought metal, but in either event is fashioned with a corrugated portion which provides grooves or recesses 22 to receive the lever handles when they are turned down to vertical position, with the door either locked or ajar, and the bolts accordingly adjusted for the purpose of fastening the door. With the lever handles positioned in their recesses, the latch 19 may slide in its base plate, over the handles and lock them against movement as shown, and the latch bar is provided with a flanged, perforated end 23, complementary to the perforated end flange 24 of the base plate in order that a sealing or locking device, indicated in dotted lines at 25 in Fig. 6, may secure the latch in closed position over the lever handles of the bolts.

If desired or required a pin 26 may be attached as by a chain at the toe of the door 2, which when not in use is retained in the keeper 27 on the door, to be inserted in a socket in the door sill when the door is held ajar, as in Fig. 2, to prevent forward jamming or movement of the door.

From the above description taken in connection with my drawings it is apparent that I have invented a car door fastening that is readily applicable for use with the ordinary style of doors and performs the functions of the "set-in" car doors, with great security and considerably less expense, and the close relationship provided between the closed door and the car side or door frame renders the door almost if not entirely weather proof. The door is securely fastened against pilfering or surreptitious opening, and as will be noted, it may be adjusted to several positions, but only one seal is required to lock the door in any of these positions, and as the door is fastened by its bolts, no strain is exerted against the seal, and consequently accidental breaking of the seal is eliminated. And as before stated, changes and alterations may be made in the construction and application here shown, without departing from the spirit of my invention, the structure shown in the drawings being merely one exemplification of the invention.

What I claim is—

1. The combination in a car door fastening, with the door and car, of a pair of opposed slidable and rotatable bolts on the door and, securing means therefor adapted to lock either or both bolts, a fixed keeper for one bolt, and a series of selective, independently movable blocks for the other bolt.
2. The combination with the car door and its pair of opposed slidable bolts and a sin-

gle latch for the bolts, of a fixed keeper on the car for one bolt, and a series of selective, pivoted keepers on the car for the other bolt, said keepers being independently movable by gravity to inoperative position.

3. The combination with the alined, slideable and rotatable bolts and their keepers, of a recessed base plate on the door, angular lever handles on the bolts adapted to fit 10 into said recessed plate, and a single sliding latch for retaining either or both said handles in the recessed plate.

4. The combination with the slideable and rotatable bolts one of which is provided with 15 a series of selective blocks for holding the door in adjusted position, angular handles on the bolts, a recessed base plate to receive said handles, and a retaining device common to both said handles.

20 5. The combination with the alined oppositely slideable, and rotatable bolts, each having a bent end, a series of spaced, selective keepers for one of the bolts and a fixed keeper for the other bolt, whereby the door

may be locked in adjusted position, said 25 bolts each having a cut-away portion at its free end and said keepers adapted to be frictionally engaged by the cut-away portions of the bolts when they are shot and said bolts, when turned to locking position 30 adapted to turn with a cam action in the perforated keeper, of a recessed base plate to receive said bent ends when the bolts are in locked position, and a slideable latch movable in said base plate to retain the bent ends 35 as described.

6. The combination with the alined, oppositely slideable, and rotatable bolts, each having a bent end, a series of spaced, selective 40 keepers for one of the bolts and a fixed keeper for the other bolt, whereby the door may be locked in adjusted position, of a recessed base plate to receive said bent ends when the bolts are in locked position, and a slideable latch movable in said base plate 45 to retain the bent ends as described.

JAMES GILLAM WOOD.
